UNITED STATES PATENT OFFICE.

LOUIS FRANK, OF FLUSHING, AND ISEDORE GUREVITCH, OF BROOKLYN, NEW YORK,
ASSIGNORS TO GREENPOINT METALLIC BED CO. INC., OF BROOKLYN, NEW YORK,
A CORPORATION OF NEW YORK.

BEDSTEAD.

Application filed February 12, 1925. Serial No. 8,603.

The invention relates to improvements in bedsteads, and pertains particularly to the corner posts and bedstead sides and to corner fastening members for securing said sides at 5 their ends to the corner-posts.

One purpose of the invention is to provide a bedstead having broad or deep sides of wood, and a further purpose of the invention is to provide adequate corner fastening members for securing the ends of the deep or 10 broad bedstead sides to the corner posts. The bedstead sides have secured at their inner faces and away from the horizontal longitudinal edges of said sides, angle iron 15 supporting rails which are adapted to receive any usual style of bedstead spring, whether of box type or otherwise, and support the same below the upper edges of the bedstead sides. The angle iron supporting 20 rails are secured to the inner faces of the bedstead sides and at their ends cooperate with certain corner fastening members riveted thereto for engagement with special 25 corner fastening members rigidly secured to the vertical inner or facng sides of the corner posts. While we prefer to form the bedstead sides of wood, we realize that these 30 wooden sides may be imitated in sheet steel, and hence we do not limit the invention solely to the employment of wood in the construction of the broad or deep bedstead sides.

Our invention provides a bedstead which is attractive and which is effective in that all 35 the parts thereof are held in very firm relation to one another and yet may be disassembled without difficulty. A further feature of the invention is to so construct the metallic portions applied to the wooden bedstead sides that said sides may be reversed 40 end for end and turned upside down and applied to the corner fastening members secured to the corner-posts, thereby causing the supporting flange for the bedstead spring to attain a lower position, to suit the 45 nature of the springs, than would be the case if said sides were not reversible.

The invention will be fully understood from the detailed description hereinafter presented, reference being had to the accompanying drawings, in which:

Fig. 1 is a vertical transverse section through a bedstead constructed in accordance with and embodying my invention, the

section being on the dotted line 1—1 of Fig. 4;

55

Fig. 2 is a detached perspective view, partly broken away and partly in section, of one of the corner posts of the bedstead and the corner fastening members carried thereby for cooperaton with the coacting corner 60 fastening members carried by the side of the bed;

65

Fig. 3 is a perspective view, partly broken away, of one end portion of a side of the bed and the corner fastening members carried 70 thereby for cooperation with the corner fastening members carried by the corner post and shown in Fig. 2;

75

Fig. 4 is a horizontal section, partly broken away, through the bedstead, taken on the dotted line 4—4 of Fig. 1;

78

Fig. 5 is a vertical longitudinal section, partly broken away, and on a larger scale, through the bedstead, taken on the dotted line 5—5 of Fig. 4;

80

Fig. 6 is a horizontal section through a portion of the same, taken on the dotted line 6—6 of Fig. 5;

85

Fig. 7 is a vertical transverse section through a portion of a modified embodiment 80 of the invention, the modification consisting in making the side of the bedstead of sheet steel instead of wood, which is the material shown in Fig. 1, and

85

Fig. 8 is a fragmentary vertical section through a portion of the bed and is presented to illustrate that the side of the bed may be inverted, that is, turned upside down and turned end for end and applied to the corner fastening members carried by the bed posts, 90 the construction shown in Fig. 8 presenting the same corner fastening members as those shown in the other figures of the drawings.

95

In the drawings, 10 denotes the head-frame of the bedstead, 11 the foot-frame 95 thereof, 12 the bedstead sides, and 13 the corner posts. The sides 12 are preferably of wood, but may be imitated in sheet steel, as I indicate at 14 in Fig. 7. The head and foot frames 10, 11, respectively, may be of 100 any suitable construction, and two of the corner-posts 13 are secured to the ends of the head-frame and two of said corner-posts are secured to the ends of the foot-frame. The corner-posts 13 are preferably rectangular 105 in cross-section and have secured to their in-

ner facing transverse surfaces, the corner-fastening member illustrated in perspective in Fig. 2, this corner fastening member comprising an angle plate, one flange 15 of which is sunken into the surface of the corner-post and securely fastened thereto by screws 16, the other flange 17 of said angle plate being extended longitudinally and formed with a vertical recess 18 and a hook member 19 which extends upwardly and at its inner edge 20 is tapered downwardly and inwardly toward the bottom of the recess 18 so as to form a wedge surface to coact with the corner fastening member carried by the bedstead side 12. The corner fastening member carried by the post also comprises a vertical stop plate 21 which is riveted to the flange 17 of the said angle plate and laps against the longitudinal face of the corner-post 13, as shown in Fig. 2, the outer edge 22 of said plate 21 being set outwardly from the adjacent edge 23 of the flange member 17, said edge 23 thus being offset from or standing inwardly from the edge of said plate 21. The plate 21 is secured to the angle member 17 by means of rivets 24, and hence is substantially integral with the post corner fastening member and besides performing other duties aids in the secure union of the corner fastening member with the post. I number the corner fastening member, 25 as a whole. Each post 13 is provided with a corner fastening member 25 and these members are all alike. The bed sides 12 correspond with each other and one purpose of the invention is to provide a broad or deep bedstead side and to form the same of wood, although as aforesaid, this wooden bedstead side may be imitated in sheet steel, as indicated at 14 in Fig. 7. The bedstead side 12 has plain inner and outer faces, and upon the inner face of each bedstead side is secured by screws or otherwise an angle iron supporting rail 26 which extends longitudinally of the side 12 and has one flange 27 against the face of the side 12 and its other face 28 extending horizontally and inwardly from and at right angles to the inner face of the side 12, as shown in Fig. 3. The flanges 28 of the angle iron rails 26 extend toward each other, as shown in Fig. 4, and serve to receive and support the spring which may be applied to the bed whether the spring is of box type or of metallic type, the particular construction of the spring being unimportant, the essential condition being that the angle iron rails 26 be adapted to receive and support the spring below the upper edges of the bed sides 12. The end portions of the flanges 28 of the angle iron supports 26 are cut away, as shown in Fig. 3, and this is for the purpose of permitting the bedstead side to be reversed end for end and turned upside down and applied to the corner fastening

members 25 in the manner shown in Fig. 8 in which it may be seen that the flange member 28 of the angle iron rail 26 is disposed at the lower edge of said rail, thereby allowing increased space between said flange and the upper edge of the bedstead side to receive such special style of spring as it may be desired to use on the bedstead.

To each end of the flange 27 of each supporting rail 26 is secured by a rivet 29, a corner fastening plate 30 comprising an inner tongue member 31 which engages the face of and is riveted to the aforesaid flange 27 and a vertical elongated plate member 32 which is offset from the tongue member 31 and extends outwardly toward the corner post and is spaced from the end portion 33 of the flange 27, as shown in Fig. 3. The plate member 32 is connected by a rivet 36 with the end portion 33 of the flange 27 and on this rivet 36 and between said members 32, 33 is applied a roller or bushing 37. The outer vertical edge of the plate member 32 is recessed, as at 38, leaving outwardly extending vertical projections 39, whose function is in the assembly of the parts to engage the inner vertical edge 22 of the back or stop plate 21 forming a portion of the corner fastening member 25, as shown in Fig. 5.

In the assembly of the parts of the bedstead, the bedstead sides are positioned between the corner posts of the head and foot frames, and the corner fastenings provided on the ends of the supporting rails 26 are engaged with the corner fastening members 25 of the corner posts, this engagement being effected by allowing the rollers or bushings 37 on the rivets 36 to settle downwardly into the wedge shaped recesses 18 of the corner post angle members 17, as will be understood on reference to Fig. 5, and allowing the projections 39 on the side fastening members 30 to engage the vertical edges 22 of the back or stop plates 21. The inclined or wedge edge 20 of the members 19 of the post corner fastening members 25 serve to force the projections 39 forwardly against the back plate or stop 21, as shown in Fig. 5, and hence when the ends of the bedstead side are engaged with the corner fastening members 25, said bedstead side has its ends brought up flush against the facing vertical surfaces of the corner posts, as shown in Fig. 4, and said bedstead side becomes very firmly secured in position. The broad ends of the bedstead side 12 present extended surfaces to engage the corner posts 13, and this in itself is a benefit, and the interengaging corner fastening members 25, 30 when of the construction presented firmly bind and lock the bedstead side in operative position. When the bedstead sides 12 are in operative position, the flanges 28 of the supporting angle iron rails 26 extend toward each other, as

shown in Fig. 4, and present broad rigid shelves or supports for the bedstead spring.

The construction hereinbefore described enables us to make a very attractive bedstead having vertically broad or deep wooden sides, with the supporting rails 26 wholly concealed. The construction is also such that the bedstead sides may be inverted and turned end for end and applied to the corner posts 13, as will be understood on reference to Fig. 8, the supporting flange 28 of the angle rail 26 then extending from what is then the lower edge of the flange 27.

We prefer to form the bedstead sides 12 of wood and to highly finish the same, for our bed is an attractive one, but we are aware that said sides may be imitated in sheet steel, as we indicate in Fig. 7, wherein 14 denotes the broad bedstead side formed of sheet steel and which side is equipped with the same spring supporting rail and end corner-fastening members that I illustrate in Fig. 3. We do not wish, therefore, to confine the invention in every instance to the use of wood in forming the bedstead sides 12.

What we claim as our invention and desire to secure by Letters-Patent, is:

A bedstead having head and foot frames including corner posts; an angular bracket secured to each corner post, each bracket comprising a transverse flange with its exposed surface flush with the corner post and a vertical longitudinal flange having a tapered tongue; a vertical stop-plate riveted to the inner side of each angular bracket and 35 overlying the corresponding corner post; side rails extending between the head and foot frames; fastening means carried by the side rails for engaging the corner post brackets, said fastening means including a plate to 40 bear against the side of the vertical longitudinal flange, and a transverse rivet to engage the tapered tongue, the end edge of said plate bearing against the vertical stop-plate; and supplementary side members attached to 45 said side rails to conceal the side rails and the corner fastenings, the ends of said supplementary side rails being adapted to abut the adjacent corner posts.

Signed at Brooklyn, in the county of 50 Kings and State of New York, this 3rd day of February, 1925.

LOUIS FRANK.
ISEDORE GUREVITCH.
